UNITED STATES PATENT OFFICE.

DANIEL DIVER, OF CALGARY, ALBERTA, CANADA.

MACHINE FOR THE SEPARATION OF GOLD, SILVER, AND PLATINUM FROM SAND.

1,329,113.

Specification of Letters Patent. Patented Jan. 27, 1920.

Application filed May 10, 1916. Serial No. 96,555.

To all whom it may concern:

Be it known that I, DANIEL DIVER, of the city of Calgary, Province of Alberta, Dominion of Canada, have invented new and 5 useful Improvements in Machines for the Separation of Gold, Silver, and Platinum from Sand.

The primary object of my invention is to provide a simple, convenient and efficient 10 method of separating the particles of gold, silver and platinum from the sand in which they are found, for example in river bars, gravel bars, quartz dumps and hydraulic tailings. The old system of washing the 15 mineral from the sand leaves considerable mineral with the sand even after repeated washing. This invention provides a machine with the aid of which the gold, silver and platinum are practically all separated 20 from the sand by the use of a certain process.

With the foregoing and other objects in view this invention consists in such novel features of construction, combination and 25 arrangement of parts as will be hereinafter more fully described, illustrated in the accompanying drawings and claimed.

In describing the invention in detail, reference will be made to the accompanying 30 drawing which shows a vertical cross-section of the machine constructed in accordance with this invention.

Referring more particularly to the drawings, 14 is a hollow vertical cylinder or 35 drum, the upper end being closed by a flat top; to the lower end of 14 is attached an inverted hollow truncated cone 13 to the apex of which is attached a short piece of cylindrical pipe 15; 7 is a piece of cylindrical pipe held by the collar 6, on the top 40 of said drum and vertically adjustable within said collar 6, the said pipe being inserted into the drum 14 through an opening near the center of the top; 4 is a piece of cylindrical pipe connected to the upper end of 45 the pipe 7. The cylindrical pipe 5 is inserted into the pipe 4 through an opening in the side of the pipe 4. The pipe 5 is turned downward inside the pipe 4. 3 is 50 a piece of cylindrical pipe connected to the upper end of the pipe 4; 3 is open at the top and has an opening 2 in the side; 12 is a sheet of glass covering an opening in the top of the drum 14; 11 is a sliding door 55 in the side of the drum 14; 9 is a shallow cylindrical cup set in a collar supported

by the horizontal bars 10, 10, fixed in the sides of the drum 14; the cup 9 is held directly under the pipe 7 and is removable: 8 is a cylindrical ring shaped to fit into the top of the cup 9, the lower edges of the said ring being bent inward at right angles and the upper edges of which are bent outward so as to form a flange; 23 and 24 are parts of a supporting frame work; 19 is a horizontal bar attached at each end to the uprights 23—23 of the said frame work; to the bar 19 is fixed the collar 20 which is attached around the pipe 15; 16 is a circular sprinkler attached around the lower end of the pipe 15, and 21 is a piece of pipe attached to and opening into the sprinkler 16; 35 is a shallow pan, the bottom of which slopes from all sides to the center and is drained by means of the petcock 34. The pan 35 is suspended from the bar 19 by four metal straps 17, rigidly fixed to the pan 35 and to the bar 19. 26 is a screen approximating in shape and being a little less in size than the bottom of the pan 35. The screen 26 is suspended from the bar 19 by two metal straps 17 which are rigidly fixed to said screen and to the bar 19; 30 is a cam-shaft mounted for rotation on the supporting bar 22. 33 is a wheel by which power is applied to the said cam-shaft 30; 29 is a rod attached at one end to the cam 31 and at the other end to a bracket 27 which holds the pan 35; 32 is another cam operating on the cam shaft 30; 28 is a rod attached at one end to the cam 32 and at the other end to one of the metal straps 17.

The operation of the machine is as follows:

Fluid such as steam, air or water is conducted under pressure through the pipe 5 creating a pressure downward through the pipes 4 and 7; mercury is placed in the cup 9; water is conducted by the pipe 21 into the sprinkler 16 which sprays the water on the pan 35. The sand and mineral are conducted into the top 1 of the pipe 3 and the pressure of the fluid from the pipe 5 blows the sand and mineral into the cup 9 forcing the heavy mineral into the mercury and blowing the sand out over the flanged ring 8. The particles of sand and mineral tend to separate as they pass through the pipe 7 under pressure. The sand and mineral are blown against the mercury and the heavy minerals sink into the mercury and the sand is blown off the

surface of the mercury. The mercury also amalgamates with gold and silver and the platinum will sink to the bottom of the cup. The reason that the lower edges of the ring 8 are turned inward at right angles is as follows:—It is found that in sands containing gold there are often heavy sands such as iron or black sands. When the apparatus is in operation the force of the fluid sand and mineral coming through the pipe 7 sets the mercury in motion flowing downward in the center of the cup 9 thence outward to the sides of the cup thence upward and inward toward the center. The mercury rolls from the sides of the cup to the center in a convex curve leaving a space between the mercury and the sides of the cup. The said heavy sands tend to gather in this space and being heavy will work downward into the bottom of the cup gradually forcing the mercury out of the cup. The bent lower edges of the ring 8 prevent the said heavy sands from getting down through the said space to the bottom of the said cup. These sands will then be carried upward with the other sands and blown off the surface of the mercury. The sand and any particles of mercury and other mineral which are blown out of the cup 9 are collected by 13 and 15 into the pan 35. Power is applied to the cam-shaft 30 and the pan 35 and the screen 26 are set in motion, the pan being given a lateral motion and the screen being held by metal straps rigidly fixed to the screen and to the bar 19 is given a lateral and vertical motion, the vertical motion resulting from the resultant bending of the screen. This works the sand from the bottom of the pan 35 and the mercury is allowed to settle. The motion of the screen really opens the sand so that the heavy mineral may fall through.

The mercury and gold or silver may then be separated by the methods known to the art.

The opening 2 at the upper side of the pipe 4 serves to admit air and thereby prevent the creation of any vacuum in the pipe

which would interfere with the passage of the stream of sand therethrough.

It will be observed that the lower edge of the pipe 7 is above the upper edge of the cup 9 which leaves a free space through each. The sand may be blown off the surface of the mercury, this sand being collected as explained by the casing 14 and then operated upon by the separating mechanism to recover any precious metal values therein.

From the foregoing description taken in connection with the accompanying drawings, the advantage of construction and of the method of operating this machine will be readily apparent to those skilled in the art to which this invention appertains, and while in the foregoing description the principle of the operation of this invention has been described together with various features of construction, the combination and arrangement of parts may be altered to suit practical conditions provided such alterations are comprehended within the scope of what is claimed.

I claim:—

An amalginator comprising in combination a cup, an amalgamating body therein having a substantially horizontal surface, a pipe adapted to discharge the sand or the like against the surface of said body, the lower end of the pipe being above the upper edge of the cup whereby a free space will be left through which the sand may be blown off and means for producing a fluid jet within the pipe adapted to assist in projecting the particles against the surface of the amalgamating body, a ring fitting around the edge of the cup having an inwardly turned flange adapted to prevent sand working between the amalgamating body and the cup.

In witness whereof I have hereunto affixed my signature in the presence of two witnesses.

DANIEL DIVER.
